MINERALS SEPARATION NORTH AMERICAN CORPORATION, OF NEW YORK,
N. Y., A CORPORATION OF MARYLAND.

ORE-CONCENTRATING PROCESS AND APPARATUS.

1,311,882.

Specification of Letters Patent.

Patented Aug. 5, 1919.

Application filed August 3, 1918. Serial No. 248,129.

To all whom it may concern:

Be it known that I, EDWARD HOPKINS EMERSON, a citizen of the United States, residing at Mountain Lakes, county of Morris, 5 State of New Jersey, have invented certain new and useful Improvements in Ore-Concentrating Processes and Apparatus, of which the following is a specification.

This invention comprises improvements 10 in the froth-flotation process of ore separation or concentration, and the apparatus for conducting that process. The objects of the invention are efficiency and economy of operation, and cheapness and simplicity of the 15 apparatus and its maintenance. In broad contemplation the invention is applicable either to general or to selective froth-flotation, and to the practice of the froth-flotation principle of separation or concentration 20 in many various aspects and phases with all manner of ores, liquors, frothing agents and selectivity agents, and the like. The accompanying drawings illustrate two specific adaptations of the invention.

25 In the accompanying drawings:

Figure 1 is a diagrammatic elevation of a series or battery of separators;

Fig. 2 is an enlarged corresponding view 30 of the two uppermost separators of the series and the feed box, and shows the second separator in vertical midsection;

Fig. 3 is a still more enlarged corresponding mid-sectional elevation of the hydro-air injector employed with each separator;

35 Fig. 4 is a diagrammatic elevation of a modified series of separators; and

Fig. 5 is an enlarged sectional elevation of two of the separator units of Fig. 4.

In that embodiment of the invention 40 shown in Figs. 1, 2 and 3, the ore pulp is suitably constituted and prepared for the froth-flotation process of separation or concentration, for instance by any desired admixture of liquors and frothing agents with 45 or without selectivity-modifying agents, and is then delivered to a feed box 4 at the head of an inclined trough 5 supported on a suitable structure 6 and forming a concentrates launder emptying into a concentrates 50 box 7. In the concentrates trough 5 are placed a battery or series of separating vessels or barrels 8 mounted at successive levels on steps 9. In the conduct of the process the mineral-carrying froth will overflow the

barrels and run down the trough 5 into the 55 box 7.

The pulp runs from the bottom of the feed box 4 through a pipe 10 into the top of the first separator 8 wherein the pulp is subjected to aeration and agitation and consequent froth flotation of a portion of its mineral constituents which are carried in a concentrates froth which overflows the barrel, and runs down the trough 5. Supplemental water is fed through the pipe 11 into 60 the top of this barrel and effects therein the necessary agitation and aeration, and about compensates for the amount of circuit liquor overflowing from the barrel in the form of a concentrates froth. The tailings flow upward from the bottom of the first barrel through a connecting pipe 12 into the top of the next lower separator barrel, in the manner of pulp inflow to the first barrel, and in the second barrel the aeration, agitation, and froth-flotation of concentrates are 65 repeated as in the first barrel, the aerating water being likewise supplied through a second pipe 11. Thus the pulp flows through 70 the entire series of separators from the top barrel to the bottom one whose final tailings 75 are discharged through the pipe 13; and each separator barrel delivers its overflowing concentrates froth to the trough 5 and thence to the box 7; while the common pressure main 14 supplies aerating and agitating water to all the separators through their respective jet pipes 11 and control valves 15.

The aerating and agitating operation of each separator may be described with reference to the second barrel, shown in section in Fig. 2. The injector cap 16 is screwed on the jet pipe 11, and the injector cup 17 is screwed into this cap and has air-inlet holes 18. The injector tube 19 is suspended by its flaring upper end in a central hole in the bottom of the cup 17. The barrel is 90 surrounded by a feed-pan 20 supported on legs such as 22, one of which is formed into a boss 21 making a connection for the pulp intake 95 pipe 12. A fall pipe or pulp-intake pipe 23 is screwed into a depending hub formed around the central hole in the feed pan, and the injector tube 19 hangs centrally in this fall pipe. An agitation baffle 24 is secured 100 in the barrel below the fall pipe 23, on a spider which spans the barrel.

The pulp from the connecting pipe 12

flows over the feed pan and through its fall pipe 23 into the barrel, and the liquid level in the barrel is above the lower end of the fall pipe.

5 The discharge end of the jet pipe 11 is
constricted to form a small water jet di-
rected into the flaring upper end of the in-
jector tube 19 and entraining a downward
flow of air which is supplied through the in-
10 let holes 18. The resulting mixed water-
and-air jet is discharged from the injector
tube 19 through the fall pipe 23 into the
pulp body and against the baffle 24, where-
15 by the intaken air is broken and mixed with
the pulp to form the mineral-carrying froth
which overflows the barrel between its pan-
supporting legs, while the tailings flow from
the bottom of the barrel through its outlet
20 pipe 12 into the next separator.
20 In that practice of the invention illus-
trated in Figs. 4 and 5, each separator unit
comprises two barrels 8 and 25. The bar-
rels 8 are the same as the barrels 8 of Figs.
1 and 2, but their feed pans 20 are support-
25 ed on annular metal crowns 26 which her-
metically seal the barrel tops, and from each
barrel 8 the aerated pulp flows through a
connecting pipe 27 into its companion bar-
rel 25. A baffle 28 prevents a direct flow of
30 pulp from the pipe 27 through the barrel
25 to the pipe 29 leading to the next sepa-
rating unit, so that the aerated pulp is sub-
jected to froth-flotation separation in each
barrel 25 from which the mineral-bearing
35 froth overflows.

Manifestly the invention accomplishes the general advantage of introducing the stream of thoroughly mixed air and water (e. g. from the pipe 19) into the pulp-stream 40 on its way to the agitator and separator (e. g. in the intake-pipe 23). Also, in the adaptations shown, the hydraulic driving force of the air-and-water stream is utilized to propel the commingled air-and-water 45 and pulp streams violently into the pulp body, and against a baffle, to effect the agitation necessary to form mineral-carrying bubbles, while also assisting gravity in propelling the pulp through the series of units.

50 As is well known in the art air is usually the most available and cheapest bubble forming gas but may in some instances be replaced by an equivalent gas, and the word "air" as used in the following claims is intended to include any such equivalent gas.

55 tended to include any.
The general principles of the invention
may be applied in different specific ways
by artisans and technicians in the course of
practice, and adaptations of the general idea
60 may be devised by supplemental invention,
all within the generic definitions and scope
of the following claims.

What I claim is:

1. The process of ore concentration which
65 consists in producing a stream of mixed air,

and liquid, conveying said air-and-liquid stream at high velocity into a stream of ore pulp so as to impart velocity to the combined air-and-liquid and pulp streams, and projecting the combined streams violently into a body of ore pulp in the presence of a mineral-frothing agent in a manner to distribute air through the pulp and agitate the pulp to form a mineral-carrying froth, and separating the froth. 70 75

2. The process of ore concentration which consists in producing a stream of mixed air and liquid, conveying said air-and-liquid stream at high velocity into a stream of ore pulp so as to impart velocity to the combined air-and-liquid and pulp streams, and projecting the combined streams violently into a body of ore pulp in the presence of a mineral-frothing agent in a manner to distribute air through the pulp and agitate the pulp to form a mineral-carrying froth, and separating the froth; and deriving another pulp stream from said pulp body and similarly conveying a second air-and-liquid stream into said second pulp stream so as to impart velocity thereto and similarly projecting the resulting combined air-and-liquid and pulp streams into a second body of ore pulp so as to again agitate and aerate and form mineral-carrying froth, and separating the froth. 80 85 90 95

3. Froth-flotation ore-concentrating apparatus comprising a hydro-air conduit and means for forcing a stream of mixed air and liquid through said conduit so that it will be delivered at high velocity therefrom, an agitation vessel adapted to agitate and aerate an ore pulp by the action of a flowing stream of aerated pulp, a pulp-intake conduit for such agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.

4. Froth-flotation ore-concentrating apparatus comprising a hydro-air conduit and means for forcing a stream of mixed air and liquid through said conduit so that it will be delivered at high velocity therefrom, an agitation vessel adapted to agitate and aerate an ore pulp by the action of a flowing stream of aerated pulp, a pulp-feeding fall-pipe projecting downward into said vessel so as to deliver its contents to said vessel, the hydro-air conduit being arranged to deliver its air-and-liquid stream into the pulp in the fall-pipe so as to impart velocity to the combined air-and-liquid and pulp streams delivered by the fall-pipe into the agitation vessel, and means for removing resulting mineral-carrying bubbles, 130

5. Froth-flotation ore-concentrating apparatus comprising a hydro-air conduit and means for forcing a stream of mixed air and liquid through said conduit so that it will be delivered at high velocity therefrom, an agitation vessel adapted to agitate and aerate an ore pulp by the action of a flowing stream of aerated pulp and having a baffle arranged in the path of said pulp stream, a pulp-intake conduit for such agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.
- 10 6. Froth-flotation ore-concentrating apparatus comprising a hydro-air conduit and means for forcing a stream of mixed air and liquid through said conduit so that it will be delivered at high velocity therefrom, an agitation vessel adapted to agitate and aerate an ore pulp by the action of a flowing stream of aerated pulp and having a baffle arranged in the path of said pulp stream, a pulp-feeding fall-pipe projecting downward into said vessel so as to deliver its contents to said vessel, the hydro-air conduit being arranged to deliver its air-and-liquid stream into the pulp in the fall-pipe so as to impart velocity to the combined air-and-liquid and pulp streams delivered by the fall-pipe into the agitation vessel, and means for removing resulting mineral-carrying bubbles.
- 15 7. Froth-flotation ore concentrating apparatus comprising an agitation vessel adapted to agitate and aerate an ore pulp by the action of a flowing stream of aerated pulp, a source of supplemental liquid under pressure, a hydro-air injector operated by liquid from said source to project a stream of mixed air and liquid so that it will be delivered at high velocity therefrom, a pulp-intake conduit for said agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.
- 20 8. Froth-flotation ore-concentrating apparatus comprising an agitation vessel adapted to agitate and aerate an ore pulp by the action of a flowing stream of aerated pulp and having a baffle arranged in the path of said pulp stream, a source of supplemental liquid under pressure, a hydro-air injector operated by liquid from said source to project a stream of mixed air and liquid so that it will be delivered at high velocity therefrom, a pulp-intake conduit for such agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.
- 25 9. Froth-flotation ore concentrating apparatus comprising an agitation vessel adapted to agitate and aerate an ore pulp by the action of a flowing stream of aerated pulp, a hydro-air conduit and means for forcing a stream of mixed air and liquid through said conduit so that it will be delivered at high velocity therefrom, a pulp-intake conduit for such agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.
- 30 10. Froth-flotation ore concentrating apparatus comprising an agitation vessel adapted to agitate and aerate an ore pulp by the action of a flowing stream of aerated pulp and having a baffle arranged in the path of said pulp stream, a source of supplemental liquid under pressure, a hydro-air injector operated by liquid from said source to project a stream of mixed air and liquid so that it will be delivered at high velocity therefrom, a pulp-intake conduit for said agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and a separating vessel arranged to receive the pulp from the agitation vessel and adapted to separate mineral-carrying bubbles by flotation.
- 35 11. Froth-flotation ore concentrating apparatus comprising an agitation vessel, a pulp feed box thereon, a pulp-feeding fall-pipe extending down from the feed box into the vessel, a source of supplemental liquid under pressure, a hydro-air injector operated by liquid from said source and arranged to deliver its contents into the fall-pipe, a baffle in the agitation vessel arranged in the path of the pulp stream from the fall-pipe, and means for removing mineral-carrying bubbles.

it will be delivered at high velocity therefrom, a pulp-feeding fall-pipe projecting downward into said agitation vessel so as to deliver its contents into said vessel and arranged to receive the stream of mixed air and liquid delivered by the hydro-air conduit and to have velocity imparted by such air-and-liquid stream to the combined streams delivered by it and to deliver its contents at high velocity into said agitation vessel, and means for removing resulting mineral-carrying bubbles.

40 12. Froth-flotation ore concentrating apparatus comprising an agitation vessel adapted to agitate and aerate an ore pulp by the action of a flowing stream of aerated pulp, a hydro-air conduit and means for forcing a stream of mixed air and liquid through said conduit so that it will be delivered at high velocity therefrom, a pulp-intake conduit for such agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and a separating vessel arranged to receive the pulp from the agitation vessel and adapted to separate mineral-carrying bubbles by flotation.

45 13. Froth-flotation ore concentrating apparatus comprising an agitation vessel adapted to agitate and aerate an ore pulp by the action of a flowing stream of aerated pulp and having a baffle arranged in the path of said pulp stream, a source of supplemental liquid under pressure, a hydro-air injector operated by liquid from said source to project a stream of mixed air and liquid so that it will be delivered at high velocity therefrom, a pulp-intake conduit for said agitation vessel arranged to receive ore pulp and to receive the stream of mixed air and liquid delivered by the hydro-air conduit and to have velocity imparted by such air-and-liquid stream to the combined streams delivered by it and to deliver its contents at high velocity into said agitation vessel, and a separating vessel arranged to receive the pulp from the agitation vessel and adapted to separate mineral-carrying bubbles by flotation.

50 14. Froth-flotation ore concentrating apparatus comprising an agitation vessel, a pulp feed box thereon, a pulp-feeding fall-pipe extending down from the feed box into the vessel, a source of supplemental liquid under pressure, a hydro-air injector operated by liquid from said source and arranged to deliver its contents into the fall-pipe, a baffle in the agitation vessel arranged in the path of the pulp stream from the fall-pipe, and means for removing mineral-carrying bubbles.

- 4
12. Froth-flotation ore concentrating apparatus comprising an agitation vessel, a pulp feed box thereon, a pulp-feeding fall-pipe extending down from the feed box into the vessel, a source of supplemental liquid under pressure, a hydro-air injector operated by liquid from said source and arranged to deliver its contents into the fall-pipe, a baffle in the agitation vessel arranged

in the path of the pulp stream from the fall-pipe, and a separating vessel arranged to receive the pulp from the agitating vessel and adapted to separate mineral-carrying bubbles by flotation. 10

In testimony whereof I have affixed my 15
signature to this specification.

EDWARD HOPKINS EMERSON.
